(57) **CLAIM**

The ornamental design for a hood for an automobile, as shown and described.

DESCRIPTION

FIG. 1 is a front elevational view of a hood for an automobile in accordance with our new design;

FIG. 2 is a top plan view thereof;

FIG. 3 is a front cross sectional view thereof, taken in the direction of line 3-3' of FIG. 2;

FIG. 4 is a front cross sectional view thereof, taken in the direction of line 4-4' of FIG. 2;

FIG. 5 is a front cross sectional view thereof, taken in the direction of line 5-5' of FIG. 2;

FIG. 6 is a front cross sectional view thereof, taken in the direction of line 6-6' of FIG. 2;

FIG. 7 is a bottom plan view thereof;

FIG. 8 is a right side elevational view thereof;

FIG. 9 is a left side elevational view thereof;

FIG. 10 is a front, right and top side perspective view thereof; and,

FIG. 11 is a rear elevational view thereof.

The broken lines in FIGS. 3 to 6 are for purpose of illustrating internal structure of the hood and form no part of the claimed design.
